UNITED STATES PATENT OFFICE.

GEORGE W. WELLS, OF AMESBURY, MASSACHUSETTS.

WINDSHIELD ADJUSTER.

Application filed April 16, 1926. Serial No. 102,562.

This invention relates to that class of devices which are employed to adjust the pivotally supported panel of a windshield in a closed body automobile, which comprise 5 an arm or lever which is pivoted at one end to the panel and is adjustably and pivotally connected to the frame in which the panel is mounted.

While adjusting devices of this character 10 are extensively used, they have been found to have certain undesirable features, particularly in that the means for adjustably and pivotally connecting the arm to the frame is liable to become loose, even though it 15 has been tightened as securely as possible by hand, so that the panel will not be held in its adjusted position, or the parts will rattle. Also, it has been attempted to construct the adjusting means so that the panel 20 cannot be swung from its closed position by pressure thereon, even though the clamping nut, with which such devices are usually provided, has not been tightened, but these arrangements have been found to be unsatisfactory, for the reason that it is difficult 25 to set the pivot screw in such a position that the panel will be closed firmly against its seat, when the parts are in the locked position, also, as the panel is seated against a 30 packing and this packing yields in time, even if the parts are properly set at the time of installation, they will not be so set for later conditions.

The objects of my invention are to provide 35 a form of sliding and pivotal connection between the adjusting arm and casing in which the sliding connection between the arm and pivot bolt may be securely locked, by means of a clamping nut, or screw, with but slight 40 effort, and in which the liability that the locking means will become loosened in use is practically obviated.

I accomplish these, and other objects of 45 my invention, in the manner hereinafter described and illustrated in the accompanying drawing, in which:

Fig. 1 is a sectional view of windshield showing an adjusting means for the panel, embodying my invention, in side elevation.

50 Fig. 2 is a similar view, showing the panel in partly open position.

Fig. 3 is a side elevation, on an enlarged scale, of the adjusting connections, with the panel in closed position.

55 Fig. 4 is a front elevation thereof.

Fig. 5 is a sectional view, at line 5—5 of Fig. 3.

Fig. 6 is a detail perspective view of the clamping clip which I employ.

As shown in the drawing, the panel 1 is 60 mounted to swing on a pivot 2 at its upper edge, and to seat against the frame 3 to close the opening therein.

According to my invention a bracket 4 is 65 secured to the inner side of the panel adjacent the middle thereof, and an adjusting arm or lever is provided, which comprises a straight bar 5, having flat parallel sides, and similar edges, said bar having an arm 6 at one end which extends from one edge 70 thereof, and is connected by a pivot 7 to the bracket 4, said arm 6 being extended for a substantial distance from the edge of the bar at an angle somewhat less than a right angle, so that the pivot 7 is located in such 75 a position that a line from its center at right angles to the bar will intersect the same. A screw threaded socket 8 is secured to the frame 3 and a screw 9, having a knurled head 10, is threaded therein with its center 80 line parallel to the center line of pivot 7.

A U-shaped clip 11, of resilient metal, is 85 provided having the inner surfaces of its intermediate portions, and its side portions 12, shaped to correspond to the edge and sides respectively of the bar 5, said clip being placed astride said bar and having its side portions project beyond the edge of the bar at which its arm 6 projects, said 90 side portions each having an aperture 13 in the end portions thereof, thru each of which said screw 9 is passed before it is screwed into the socket 8. A clamping face is formed on the end of the socket 8, and a shoulder is formed on the head of screw 9, so that, when the latter is screwed into 95 the socket, the end portions of the clip will be clamped therebetween and sprung together. When the side portions of the clip are in normal position, the bar 5 may slide 100 freely therein, but a slight springing together of said side portions will cause said parts to be locked together. The bar 5 will thus be held in the clip 9, so that it will be 105 pivotally mounted on the screw 9, and, at the same time, will be slidable within the clip.

The socket 8 is so arranged that the axial line of the screw 9 is at a substantial distance above a horizontal line thru the axial 110

line of the pivot 7, which connects the link to the panel, when the latter is in closed position, and assuming that it is held in a perpendicular position when closed, as shown in Figs. 1 and 3. If the panel is held in a forwardly inclined position when closed, then the axis of the screw would be located at a corresponding distance from a line which is perpendicular to the panel and passes thru the axis of pivot 7. The arrangement is also such that, when the panel is in closed position, the bar 5 will be held nearly parallel thereto, as shown in Fig. 1. When the panel is to be swung from its closed position, the bar 5 may be used as an operating lever by pulling rearward on the upper end thereof, so as to cause the same to swing on the screw 9 as a fulcrum and thereby force the end which is connected to the panel outward. As the panel is swung outward, the clip will swing on the screw 9 and, at the same time, the bar will slide in the clip, and, when the screw 9 is tightened, the end portions of the clip will be clamped between the head of the screw and the top of the socket 8, so that the clip will be locked thereby against swinging movement. The same action causes the side portions of the clip to be clamped against the side faces of the bar 5, so that there will be a strong frictional engagement therewith, so as effectively to prevent sliding movement of the bar in the clip. Consequently, as swinging movement of the panel is only permitted when the clip is swung on its pivot and the bar slides in the clip, by tightening the screw 9, the panel will be held in adjusted position by two separate friction locks, and with this construction a comparatively slight tightening of the screw 9 will securely lock the panel in adjusted position.

The construction not only permits the bar to lie close to, and approximately parallel to the panel when the latter is in closed position, but also enables the user to force the panel to closed position by pressing forward on the upper end of the bar 5, and provides for yielding of the packing against which the panel seats and for a certain leeway in locating the position of the socket 8 when the device is installed. When the panel is in closed position, if the screw is tightened sufficiently to bring the clamping surfaces into contact, without actually forcing them together, the panel cannot be opened by a pressure which would be likely to be directly applied thereto under any ordinary conditions, on account of the short leverage which this force would have in acting to cause movement relative to the locking screw 9.

I claim:

1. In combination with a windshield having a frame and a panel mounted to swing thereon, means for adjusting said panel comprising a bar having a pivotal connection

at one end with the panel, a clip pivotally mounted on the frame and slidably connected to said bar and means for forcing opposite portions of said clip against the sides of the bar, to lock the bar against sliding movement in the clip. 70

2. In combination with a windshield having a frame and a panel mounted to swing thereon, means for adjusting said panel comprising a bar having a pivotal connection at one end with the panel, a clip in which said bar is slidably mounted, and a pivot screw mounted in the frame and extending thru opposite portions of the clip, to clamp said portions against the bar and provide a pivotal support therefor. 80

3. In combination with a windshield having a frame and a panel mounted to swing thereon, means for adjusting said panel comprising a bar having a pivotal connection at one end with the panel, a resilient U-shaped clip arranged astride said bar and in which the bar is adapted to slide, a pivot screw extending thru the end portions of the clip to one side of the bar and mounted in, and having a threading connection with said frame to provide a pivotal support for said clip, and means on the screw and on the frame for engaging the outer sides of said clip end portions, to force the opposite portions of the clip into frictional locking engagement with the bar. 90

4. In combination with a windshield having a frame and a panel pivotally mounted therein to swing between positions to open and close the frame opening, a bar having an arm at one end extending in transverse relation thereto, said arm having a pivotal connection with the panel, whereby said bar may be swung into approximately parallel relation with the panel, a U-shaped clip arranged astride said bar with its end portions projecting beyond the bar at the same side thereof as that at which said arm is located, a screw extending thru said end portions of the clip at said side of the bar and having a threaded connection with said frame, to provide a pivotal support for the clip, and means on said screw and frame for clamping the opposite portions of the clip against said bar, to lock the bar against sliding movement in the clip. 100

5. In combination with a windshield having a frame and a panel pivotally mounted therein to swing between positions to open and close the frame opening, a bar having an arm at one end extending in transverse relation thereto, said arm having a pivotal connection with the panel, whereby said bar may be swung into approximately parallel relation with the panel, a screw threaded socket mounted on the frame in a position in which its center is above a perpendicular line to the panel thru the center of said pivotal connection and having a clamping 110 120 125 130

face, a **U**-shaped clip arranged astride said bar and having its end portions extending at the side of the bar at which its said arm is located, a screw extending thru said end portions at said side of the bar and threaded in said socket to provide a pivotal support for said clip, and a shoulder on said screw for engaging the outermost end portions of the clip, whereby said end portions may be clamped between said shoulder and said face to lock said clip against swinging movement on said screw and to force opposite portions of the clip against the sides of said bar, to lock the bar against sliding movement in the clip.

6. In combination with a windshield having a frame and a panel pivotally mounted therein, to swing between positions to open and close the frame opening, a straight bar having flat, parallel faces at opposite sides

thereof and having an arm at one end extending in transverse relation thereto from one edge, said arm having a pivotal connection with the panel permitting said bar to be swung in approximately parallel relation to the panel, a **U**-shaped clip arranged astride said bar and having the opposite portions thereof slidably engaged with the side faces of said bar and projecting beyond the edge of the bar from which said arm projects, and a clamping screw extending thru said end portions and threaded in the frame to provide a pivotal support for said clip and adapted and arranged to clamp said clip portions against said faces to lock the same thereto.

In testimony whereof, I have signed my name to this specification.

GEORGE W. WELLS.
